The ornamental design for a stylus with ballpoint pen, as shown and described.

DESCRIPTION

FIG. 1 is a front perspective view of a stylus with ballpoint pen according to a first representative embodiment of our new design, wherein a cap covers the ballpoint pen; FIG. 2 is a rear perspective view of the stylus shown in FIG. 1;

FIG. 3 is a front view of the stylus shown in FIG. 1; FIG. 4 is a side view of the stylus shown in FIG. 1, the opposite side of the side shown in FIG. 4 being a mirror image thereof and therefore not shown;

FIG. 5 is a rear view of the stylus shown in FIG. 1; FIG. 6 is a top view of the stylus shown in FIG. 1; FIG. 7 is a bottom view of the stylus shown in FIG. 1; FIG. 8 is a front perspective view of the stylus shown in FIG. 1 with the cap removed;

FIG. 9 is a rear perspective view of the stylus shown in FIG. 8;

FIG. 10 is a front view of the stylus shown in FIG. 8; FIG. 11 is a side view of the stylus shown in FIG. 8, the opposite side of the side shown in FIG. 11 being a mirror image thereof and therefore not shown;

FIG. 12 is a rear view of the stylus shown in FIG. 8; FIG. 13 is a top view of the stylus shown in FIG. 8; FIG. 14 is a bottom view of the stylus shown in FIG. 8; FIG. 15 is a front perspective view of a stylus with ballpoint pen according to a second representative embodiment of our new design, wherein a cap covers the ballpoint pen; FIG. 16 is a rear perspective view of the stylus shown in FIG. 15;

FIG. 17 is a front view of the stylus shown in FIG. 15; FIG. 18 is a side view of the stylus shown in FIG. 15, the opposite side of the side shown in FIG. 18 being a mirror image thereof and therefore not shown;

FIG. 19 is a rear view of the stylus shown in FIG. 15; FIG. 20 is a top view of the stylus shown in FIG. 15; FIG. 21 is a bottom view of the stylus shown in FIG. 15; FIG. 22 is a front perspective view of the stylus shown in FIG. 15 with the cap removed;

FIG. 23 is a rear perspective view of the stylus shown in FIG. 22;

FIG. 24 is a front view of the stylus shown in FIG. 22;
(Continued)

FIG. 25 is a side view of the stylus shown in FIG. 22, the opposite side of the side shown in FIG. 25 being a mirror image thereof and therefore not shown;

FIG. 26 is a rear view of the stylus shown in FIG. 22;

FIG. 27 is a top view of the stylus shown in FIG. 22; and,

FIG. 28 is a bottom view of the stylus shown in FIG. 22.

The broken lines in the drawings show portions of the stylus which form no part of the claimed design, while the solid lines in the drawings form part of the claimed design, the solid lines also provide written description of prospective embodiments with aspects that are not claimed when one or more of the solid lines are amended to broken lines.
